UNITED STATES PATENT OFFICE

WILLIAM MICKEL BOENNING, OF MANITOWOC, WISCONSIN

FOLDING FURNITURE LEG

Application filed October 1, 1931. Serial No. 566,243.

This invention appertains to furniture and specifically to folding furniture legs of the type particularly adapted for use in connection with folding card tables and the like.

5 One of the primary objects of this invention is the provision of novel means of connecting the leg in position, so that the leg can be readily and easily swung by an operator either to its folded or set position and at the same time firmly held against accidental movement, either in its folded or operative position.

10 Another salient object of my invention is the provision of a novel bracket carried by the table top to which is hingedly connected, the swinging leg, the bracket being of such construction as to firmly brace the table top and at the same time form an efficient hinge for the leg.

15 20 A further important object of my invention is the provision of a novel swinging brace carried by the bracket and slidably connected to the leg, the leg and swinging brace having a novel co-operative means for holding the leg against accidental swinging movement when the leg is either in its folded position or in its set-up operative position.

25 30 A still further object of my invention is to provide a novel swinging leg structure for collapsible card tables of the above character, which will be durable and efficient in use, one that will be simple and easy to manufacture and one which can be placed upon the market at a reasonable cost.

35 40 With these and other objects in view, the invention consists in the novel construction, arrangement and formation of parts, as will be hereinafter more specifically described, claimed and illustrated in the accompanying drawing:

45 Figure 1 is a fragmentary side elevation showing a portion of a table with one of the side rails removed and illustrating the leg in its folded position, the view being taken on the line 1—1 of Figure 2;

50 Figure 2 is a fragmentary bottom plan view of a table showing the leg in its folded position, with parts thereof broken away and in section, illustrating structural details;

55 Figure 3 is a fragmentary side elevation

of the table, equipped with my invention, showing the leg in its extended set-up operative position;

Figure 4 is a fragmentary bottom plan view of a table showing the leg in its set-up 55 position, the leg being shown in section;

Figure 5 is an enlarged fragmentary detailed view taken substantially on the line 5—5 of Figure 3, looking in the direction of the arrows, illustrating the connection between the folding brace and the leg, the leg being in its locked set-up position;

Figure 6 is a view similar to Figure 5, showing the leg before the same reaches its operative position.

65 Figure 7 is a side elevation of the table, equipped with my invention, showing the leg in its extended set-up position.

70 Referring to the drawing in detail, wherein similar reference characters designate corresponding parts throughout the several views, the letter "A" generally indicates a table equipped with my invention. As shown, the table embodies a top 10 having secured to its side edges the depending side 75 rails 11.

75 80 As in the usual arrangement of folding tables, the legs 12 of the table are adapted to be folded flat against the inner face of the top 10 and to lie in close proximity to the side rails 11 when the legs are in their folded position.

85 90 In accordance with my invention I provide novel corner brackets 13, which are secured to adjacent side rails 11 by means of fastening elements, such as screws 14. The bracket 13 is provided adjacent one end with a folded portion 15 forming a pivot ear for the reception of a pivot pin or bolt 16. The pivot ear 15 parallels one arm of the corner 95 bracket and this arm is provided with a pivot opening for supporting the opposite end of the pivot pin from that which is supported by the ear 15. The upper end of the leg 12 has rigidly secured thereto a brace plate 17 and the extreme upper end of the brace plate is rolled to provide a hinged barrel 18 for receiving the pivot pin 16. Thus, the leg has free swinging movement on the pivot pin. It is to be noted that the upper end of the 100

brace plate 17 is slightly curved, so as to substantially occupy all of the space between the pivot ear 15 and the parallel arm 13 of the corner bracket. This creates a friction joint which tends to normally hold the leg against swinging movement. The brace plate 17 is preferably of a substantially U-shape in cross section, so as to engage one complete face of the leg and to provide side flanges 18 and 19 for engaging opposite sides of the leg. The flange 19 is provided with a headed pivot bolt 20 and directly beyond the headed pivot bolt 20, with an up-struck locking lug 21. This lug 21 is arranged at an angle to the flange 19 as clearly shown in Figures 1 and 3.

Pivots connected to the corner bracket 13 by means of a pivot pin 22 is a swinging brace 23. The brace at its extreme outer end is provided with a keeper shoulder 24, which is adapted to be engaged by the lug 21 at certain times, as will be hereinafter more fully described. The swinging brace 23 beyond the keeper shoulder 24 is provided with a manipulating handle 25. As shown, the swinging brace intermediate its ends is sprung as at 26, so that the same will be of a resilient character to resiliently bear on the locking lug 21 at all times.

In operation of the improved device, it can be seen that when the leg 12 is in its folded position, as shown in Figures 1, 2 and 6, the swinging brace 23 bears against the lug 21 and thus the leg will be normally held in its collapsed position against accidental swinging movement.

When it is desired to move the leg 12 to its operative position, the operator grasps the handle 25 and pulls down on the leg. The headed pivot pin 20 riding in the longitudinal slot 26 in the brace will move the leg to its vertical operative position, and when the leg reaches this position, the lug 21 will snap in rear of the shoulder or keeper face 24. This will hold the leg in its operative position, as clearly shown in Figures 3, 4 and 5.

When the leg is to be returned to its collapsed position, the operator again grasps the handle 25 and swings the brace 23 over the lug 21, and the leg is then swung on its pivot to its position.

From the foregoing description, it can be seen that I have provided an exceptionally simple and durable leg supporting device for card tables and the like in which the leg will be firmly held both in its opened and closed position.

Changes in details may be made without departing from the spirit or the scope of this invention, but what I claim as new is:

I claim:

1. The combination with an article of furniture including a top and a swinging leg, of means operatively connecting the leg to the top including a hinge joint, a swinging brace

carried by the top having a longitudinal slot, said brace being sprung to define a substantially resilient leaf spring, a headed pin carried by the leg slideable in the slot, a locking lug carried by the leg beyond the headed pin and arranged at an angle to the leg, the brace frictionally bearing on the lug and having a keeper shoulder thereon for engaging the lug when the leg is in its set-up position, and a manipulating handle on the extreme outer end of the brace for manipulating the brace and leg.

2. The combination with an article of furniture including a top and depending rails carried by the top, and a swinging leg, means connecting the leg to the top including a corner angle bracket rigidly secured to adjacent rails, one of the legs of the corner bracket being folded to provide a pivot ear arranged in parallel relation to the other leg of the bracket, a plate connected to the leg of the bracket, a plate connected to the leg having a hinge barrel thereon, a hinge pin extending through the pivot ear, hinge barrel and the last mentioned leg of the bracket, the plate being provided with side flanges for engaging opposite sides of the leg, a headed pin carried by one of said flanges, a locking lug formed on the flange beyond the headed pin and arranged at an angle to the leg and a resilient brace pivotally secured to the bracket having a longitudinal slot for receiving the headed pin and a keeper shoulder for engaging the lug when the leg is swung to its operative position.

In testimony that I claim the foregoing I have hereunto set my hand at Milwaukee, in the County of Milwaukee and State of Wisconsin.

WILLIAM MICKEL BOENNING.
